[57] CLAIM

The ornamental design for a shower splash guard, substantially as shown and described.

DESCRIPTION

FIG. 1 is a perspective view of a shower splash guard showing my new design;

FIG. 2 is a top plan view thereof, the bottom being a mirror image of the top shown;

FIG. 3 is a side elevational view thereof and

FIG. 4 is an end elevational view thereof.

It is to be understood that the center portion of FIGS. 3 and 4 are broken away for ease of illustration.
